UNITED STATES PATENT OFFICE.

FREDERICK G. KEYES, OF CAMBRIDGE, MASSACHUSETTS, ASSIGNOR, BY MESNE ASSIGNMENTS, TO NATIONAL REFRIGERATING COMPANY, OF BOSTON, MASSACHUSETTS, A CORPORATION OF MASSACHUSETTS.

GAS AND LIQUIDS STORING DEVICE.

Application filed December 4, 1923. Serial No. 678,537.

My present invention relates to stills for use in refrigerating apparatus and useful in the arts generally. It relates particularly to a still having cooling coils for lowering its temperature alternately with the raising thereof.

The object of my invention is to provide a still having means for quickly cooling it and other means for quickly heating it.

10 Another object of my invention is to provide a still having means for the effective distribution therethrough of the ingoing and outgoing vapor, of heat, and rapid abstraction of heat therefrom.

15 Another object of my invention is to provide a still having therein means for supporting in distributed positions therethrough an absorbent material for the vapor used therein.

20 In stills, particularly for use in refrigerating apparatus, there is required a capacity for holding, for cooling or heating high capacity vapor absorbent material in a small space and in small units of time.

25 To deliver a great number of heat units in a small space of time I employ an electric resistance of the sheath wire type as other suitable type inserted as a unit, or cartridge into the body of the still.

30 For quickly cooling, the still I employ a coiled water conduit.

For distributing the refrigerant vapor effectively I use distributing tubes and vanes throughout the still and for holding absorbent material distributed therethrough, the vanes being assembled usually horizontally in the still and serving to conduct the heat rapidly away from the heated tube on which they are mounted.

40 Vapor delivery pipes extending the length of the still also serve to distribute the vapor throughout the still through numerous perforations along their length.

These features and others, as will appear hereinafter, are shown in the drawings, in which—

Fig. 1 is a vertical sectional view of the still showing the interior of the still and the vanes and circulating pipes mounted on the exterior of the electric heating cartridge.

50 Fig. 2 is a vertical sectional elevation showing the interior of the still and of the heater cartridge.

Fig. 3 is a sectional view along the line discharge 21.

3—3 in Fig. 1 looking in the direction of the arrow. It shows a vane in plan mounted on the heater cartridge casing.

Fig. 4 is a sectional view along line 4—4 in Fig. 2 looking in the direction of the arrow. This view shows the relation of the cooling pipe to the vanes as mounted or coiled thereabout.

Fig. 5 is a vertical elevation of a vane.

Fig. 6 is a plan view of a vane indicating in dotted lines how the vane separating extensions or tabs are stamped in the vane ring and wings from a sheet of metal.

Like numbers refer to like parts throughout the drawings.

The still 1 (see Figs. 1 to 4) has fixed therein through the head 3 the inner casing 5 having mounted therein close to its walls the electric heating coil 6 of sheath wire or other suitable heater. Vapor tight joints are made between head 3 and casing 5, and between casing 5 and head 4 at the inner end of 5. The coil 6 is removable, with head 10, for replacement, repair and so on. The terminals 7 and 8 serve to connect the coil to electric supply mains. On the casing 5 are mounted the vanes 9.

The vanes 9 (see Figs. 5 and 6) comprise flat rings 20 having extending from their outer edges the wings 16 in the same plane. Alternating with these wings are the extensions 17 which have at their outer edge the offsets 18. In the embodiment of my invention shown in the drawings the bases of the extensions are bent in the arc of a circle to conform to the circumference of ring 20 and the offsets 18 are likewise formed on the arc of a circle substantially of the same diameter as that of the said bases, whereby in assembly the vanes are nested to secure rigidity. Along the inner edge of the ring 20 is the rim 19.

In the assembly of the vanes 9 on the casing 5, the rims 19, which are of substantially the same inner diameter as the outer diameter of casing 5, serve to secure rigidity of the vanes on the casing.

Coiled about the extensions 17 is the cooling water circulating pipe 15, which is sealed through the wall of the still at its entrance and exit and whose spirals pass from one vane to the other through the spaces between the wings 16 and so on to the discharge 21.

The conduit 13 is sealed through the wall of still 1 and carries the fluid to and from the still connections through the distributors 14 with the pipes 12, which extend the length of the still and which have distributed along their lengths fairly small holes for the passage of the vapor. The ends of pipes 12 are closed except for small holes the size of those along the pipe. Over these pipes is a covering 26 of asbestos tubing for straining out dust which may be carried with the refrigerant.

The pipes 12 (which specifically exemplify conduits which extend substantially the entire length of the interior of the still; and consequently traverse the aggregate body of solid absorbent material) apertured throughout their length, provide a multiplicity of short paths for gaseous refrigerant out of or into the absorbent material at all parts thereof, reducing to a practical minimum the greatest distance which gas must travel through the body of absorbent material. Maintenance of free passage through the apertures of the tube 12 at all points along its length is therefore a condition of efficient operation of the apparatus in that thereby the time factor either of emission or absorption, is reduced to a minimum. For this reason clogging of the apertures, even locally, is to be avoided; the reticulated fibrous covering, represented by asbestos tubing 26, prevents passage of fine dust from the absorbent material into the apertures of pipe 12. Since temperatures which would deteriorate fibrous material of animal or vegetable origin, supervene on the operation of the apparatus, the refractory character of asbestos fibres is of high, if not indispensable, value.

The heads 2 and 3 are sealed to the wall of the still 1. Into the side of the still is connected the drip cock 22. Additional cooling is obtained from the pipe 23 coiled about the outside of the still, which like pipe 15 is connected to a suitable supply 25 of cold water and which discharges through 24.

Suitable absorbent material in the form of granules, powder, lumps, or briquets and so on are distributed on the horizontal surfaces of the baffles throughout the still. These vanes serve for quickly conducting heat from the heater 6 to the absorbent material distributed on said baffles, the latter being of metal and much better heat conductors than the absorbent material.

What I claim is:

1. In a still, in combination, a closed outer casing, an inner casing sealed into the wall of said outer casing, an electric heating coil removably mounted in said inner casing, vane plates mounted in said outer casing, a coil of pipe mounted in said outer casing whose windings pass around said inner casing and between said vanes, said coiled pipe

being sealed at either end through the wall of said outer casing, and a vapor delivery pipe sealed through the wall of the outer casing and connected to distributing pipes extending the length of the still and being perforated with a large number of small holes. 70

2. In a still, a vane mounted therein comprising a flat ring having a perpendicular rim turned along its inner edge, and a plurality of spaced apart tabs cut in the width of said ring and bent perpendicular to the plane of said ring, the metal of the said ring between said tabs forming wings continuous with the annulus and in the plane thereof. 75

3. In a still, a vane mounted therein comprising a flat ring having a perpendicular rim turned along its inner edge, a plurality of spaced apart tabs cut along its outer edge and bent perpendicular to the plane of the ring, and offsets on the outer edges of said tabs, the inside diametrical dimension of said offsets being substantially the same as the outside diametrical dimensions at the bases of said tabs. 80

4. In a still, a vane comprising a flat ring having a perpendicular rim along its inner edge, a plurality of spaced apart wings along its outer edge and in the plane of said ring, and a plurality of tabs perpendicular to the ring plane along its outer edge and alternately arranged in the said wings, said tabs having offsets at their upper edge the inner diametrical dimension of which offsets is substantially equal to the outer diametrical dimension at the base of said tabs. 90 100

5. In a still, a casing, an absorbent in said casing, piping in said casing for the ingress and egress of fluid to said absorbent, a reentrant chamber in said casing, a header or cap for said reentrant chamber, a heating member in said chamber and mounted on said header and removable therewith, and a covering of porous asbestos for said perforated piping. 105

6. In a still, in combination, a closed outer casing, an inner casing sealed into the wall of said outer casing, heating means for said inner casing, vane plates mounted in said outer casing and in contact with said inner casing, a coil of pipe mounted in said outer casing whose windings pass around said inner casing and in contact with said vanes, said coil pipe being sealed at either end through the wall of said outer casing, a vapor delivery pipe sealed through the wall of the outer casing and connected to distributing pipes extending the length of the still and being perforated with a large number of small holes. 110 115 120

7. In a still, in combination, a closed outer casing, an inner casing sealed into the wall of said outer casing, heating means for said inner casing, vane plates mounted in said outer casing, a coil of pipe mounted in said

- outer casing whose windings pass around said inner casing and between said vanes, said coil pipe being sealed at either end through the wall of said outer casing, a vapor delivery pipe sealed through the wall of the outer casing and connected to distributing pipes extending the length of the still and being perforated with a large number of small holes, a covering of asbestos for said pipes and the holes therein, and absorbent material distributed through said still.
8. In a refrigerating apparatus of the type described, a still, a conduit therein for the passage of vaporized refrigerant comprising a tube apertured substantially throughout its length, and refractory fibrous material covering the apertures of said tube.
9. In a refrigerating apparatus of the type described, a still, a conduit therein for
- the passage of vaporized refrigerant comprising a tube apertured substantially throughout its length, and reticulated fibrous material covering the apertures of 25 said tube.
10. In a refrigerating apparatus of the type described, a still, a conduit therein for the passage of vaporized refrigerant comprising a tube apertured substantially 30 throughout its length, and a porous asbestos tube enclosing said apertured tube.
11. In a refrigerating apparatus, in combination, a still, a gas or vapor conducting member communicating with the interior 35 of said still at a multiplicity of points through short paths, and a filter of asbestos across each of said paths.

In testimony whereof I hereto affix my signature.

FREDERICK G. KEYES.
